PRINTING-ROLLER ETCHING MACHINE
OF THE SPRAY TYPE

Jørgen Bock and Eugene V. Hartman, Endicott, and Philip A. Tatusko, Endicott, N.Y., assignors to International Business Machines Corporation, New York, N.Y., a corporation of New York

Filed Dec. 27, 1957, Ser. No. 705,585

1 Claim. (Cl. 156—345)

This invention relates to machines for etching metal. It has a more specific relation to an improved machine for producing a relief in the surface of a metal plate, such as magnesium or the like which is soluble in an aqueous acid solution, for the purpose of bringing in relief type characters in making printing plates.

In the conventional method of making a metal printing surface, as in making a photoengraving of an acid-soluble metal such as magnesium, zinc, and their alloys, a light sensitive coating or enamel is applied to the metal surface which is usually flat or cylindrical. The coated surface is exposed to light through a negative having an image therein so as to produce a corresponding image in the coating. The exposed coated surface is developed forming an acid resistant coating in the form of the image produced by the exposure. The acid resistant coating, which is referred to as a resist, is usually further hardened as by a hardening treatment which increases its resistance to the etching acid. The surface of the metal bearing the so prepared resist is then subjected to etching by an acid.

The etching is usually carried out with nitric acid suitably diluted with water, the acid solution being usually splashed or otherwise impinged against the object. The acid solution attacks the bare portions of the metal, that is, the portions of the object denuded of the light sensitive material in the developing operation. The rest of the metal surface is protected by the resist from direct attack by the acid which does not penetrate the resist. As the etching proceeds, metal from the bare portions of the object dissolves away, leaving the adjacent image in vertical relief. As soon as a moderate depth of etch is made in this way, attack by the acid in a lateral direction on the metal supporting the acid-resisting image becomes noticeable and the resist may be undercut slightly around its edges.

It is recognized in the art that undercutting of the type walls is very objectionable because the shoulders or side cuts in the side walls of the type provide recesses in which dirt and ink may lodge and cause fuzzy or blurred impressions when printing is effected from such etched printing plates. The elimination of such undercutting has been the object of improvements disclosed in the past among which are those disclosed in Patents Nos. 2,640,673, 2,640,674, 2,640,675, 2,640,676 and 2,640,677. In general, the specifications of these patents specify that the improvements are predicated upon the discovery that by including in the acid etching bath, and impinging the bath composition against the object to be etched, certain agents which produce a removable acid resistant film that exerts a controlling effect on the dissolving action of the acid, the dissolving action of the acid normal to the surface of the work is not adversely affected while the dissolving action laterally, that is, in a direction which tends to dissolve away metal in relief and undercut the resist, is substantially reduced.

The solution recommended, and preferably employed in the present machine consists of the metal dissolving nitric acid etching solution in a mixture of diethylbenzene and "Aerosol," which two latter are herein the coating or film ingredients for protection against undercutting of the type walls. While this solution has been found efficient for rapidly etching flat magnesium plates the utilization of the

2

etchant when printing cylinders were processed by prior art machines did not produce the desired results, and undercutting of the type walls was prominent to an objectionable extent.

To this end, a machine which is disclosed in applicants' copending application, Serial No. 671,233, filed July 11, 1957, now abandoned, has been developed to improve the application of the etchant with the protective film to the printing cylinder. Said machine utilizes a nozzle spraying system which discharges a mist-like spray on the printing cylinder perpendicularly to the surface. The force of the spray penetrates the film to reach and etch the metal. The perpendicular emission of the spray overcomes, to a great extent, the undercutting along radial lines. This machine, as in the present machine, provided for both continuous rotation of the printing cylinder and axial reciprocation, both of such movements combining to spread the protective film over the surface of the metal and build up the film protection along axial lines to give the side walls along axial lines additional film protection.

In the machine of the above identified application the printing cylinder was mounted isolated from and above the tank holding the etching solution, and therefore was not submerged in the etching solution in the tank. This allowed the natural force of gravity to drain off the etching solution into the tank, and with the result that the draining off of the film from the cylinder provided relatively less side-wall protection along radial lines.

In the machine of the above identified application, the horizontal rotation of the cylinder carried the protective film around the surface of the cylinder which caused the film to build up more on axial lines of the cylinder than on radial lines. This gave the side-walls of the axial lines somewhat more protection against undercutting so that they did not etch the cylinder laterally as much as along radial lines, which received less side-wall protection due to the natural force of gravity, allowing the Aerosol-diethylbenzene film to drain off more readily.

Irrespective of the above disadvantages admirable results were obtained from this improved machine and printing cylinders were produced in a faster time and contained relatively little lateral or radial undercutting of the type. To the end that further improvements might be made, further research and development resulted in an improved machine shown in the present application and which discloses an improved etching applying means overcoming all objections to the prior machine.

It is, therefore, the main object of the present invention to devise a metal etching machine of the spray type which utilizes a film protective ingredient and apply the etchant in an improved manner to the printing cylinder so that undercutting of the type is equally prevented along radial and axial lines.

A still further object of the present invention is to provide an improved etchant applying means comprising a spray nozzle system for directing etchant sprays perpendicularly to the cylinder surface in combination with means to retain the cylinder partially submerged in said etchant whereby gravity drain-off of prior machines is prevented and the protective film of the etchant is more evenly distributed as the cylinder is rotated.

A still further object is to provide a spray nozzle system which directs an etchant fluid to the printing surface at the point where the printing surface emerges from the bath in which the printing cylinder is immersed and rotates therein, whereby the amount of side flow after impingement is reduced.

Other incidental and also relatively important objects will be apparent as the improved etchant applying means is understood. As the description is developed such improved construction and improved results will be explained in more detail.

Other objects of the invention will be pointed out in the following description and claims and illustrated in the accompanying drawings, which disclose, by way of example, the principle of the invention and the best mode, which has been contemplated, of applying that principle.

In the drawings:

FIG. 1 is a perspective view of the assembled etching machine embodying the present improvements.

FIG. 2 is an elevational view of the left end of the machine, as viewed in FIG. 1.

FIGS. 3 and 3b are elevational views of the rear of the machine taken on the line 3a, 3b of FIG. 2.

FIG. 4 is a sectional view taken through the tank at the rear on the line 4—4 of FIG. 2 to show the relationship of the nozzle spray devices and the printing cylinder rotating and axially shifting means.

FIG. 5 is a sectional view taken on the irregular section line 5—5 of FIG. 4.

FIG. 6 is a transverse sectional view taken on the section line 6—6 of FIG. 4, but upon an enlarged scale.

FIG. 7 is a detail view showing principally the printing cylinder rotating means.

FIG. 8 is a detail view of the cam which effects the axial shifting of the printing cylinder during its rotation.

Assembled Machine

The external appearance of the assembled machine is best shown in FIG. 1 as it is viewed by an operator employing it for etching printing cylinders. However, as will also appear in other views, the framework of the machine comprises vertical and horizontal struts 10 which are bolted together to carry suitable base members, brackets, etc. for supporting the machine units. The machine is preferably open at the rear for ventilation and service purposes but is covered at the front and sides for better appearance by stainless steel panels 11 and 12. The panels at the ends or sides may also be removable to give, as shown in FIG. 1, access to the interior units for the purpose of inspection and adjustment. It is preferable to use stainless steel for the panels because it is resistive to the acidulous etching bath employed herein.

The top of the cabinet is covered by a stainless steel cover 13 having a work surface or apron 14 and a relatively deep sink 15 over which is placed a mixing faucet assembly 16. At the left of the sink there is disposed a hinged cover plate 17 which is over an opening in the apron 14 registering with the tank to be subsequently described. To the rear of the hinged cover plate 17 there is fixedly secured a panel 18 carrying a main line power switch button 19, and three motor drive initiating buttons 20, one for the circulating motor and pump, and second for the motor for rotating and axially reciprocating the printing cylinder, and the third for the spray motor and pump.

In addition, there is provided, on the panel 18, a pressure gauge 25, a settable electric timer 26, a temperature gauge 27, and a pressure regulating knob 72. The electric timer 26 is in series with the spray motor, thus making it possible to select the etching period and have the motor shut off automatically after this period has elapsed. During this period the spray motor reverses its rotation. The pressure gauge 25 indicates the pressure of the fluid directed to the spray nozzles, and the thermometer 27 indicates the temperature of the etching bath.

In FIG. 3a there is shown the commercial device known as the "Electropulse" 28 which has suitable manual adjustments and electrical controls to the spray motor to reverse its direction, and after unequal periods, or unequal numbers of rotation in the two directions.

Etching Tank

The tank 30 which contains the etching fluid is a substantially square metal box formed of stainless steel

plate which is not subject to the corrosive action of the ingredients of the etching fluid and said tank is fully open at the top and is covered by the hinged cover 17.

5 There is located in the tank above the level of the solution the drive for rotating the arbor carrying a printing cylinder to be etched. The spray pump receives the fluid from the bottom of the tank and discharges it above the fluid level to the spray nozzles in the tank. The circulating pump likewise takes fluid from the bottom of the tank and discharges it back into the tank to keep the ingredients properly mixed.

15 There is also submerged in the tank a coil 25 (FIGS. 2 and 4) connected to the temperature gauge 27 having a temperature sensitive bulb which controls the refrigeration unit R.U. (FIG. 2) to keep the temperature of the etchant within a desired range. The etching tank is also provided with a cooling coil 36 (FIGS. 2 and 4) located at the bottom of the tank and also submerged in the etchant.

20 For communication between these different units there are a plurality of tubes and connectors and a drive shaft passing through a wall of the tank, most of them passing through the back wall of the tank with suitable bushings to prevent leakage of the fluid.

Refrigeration Unit

The refrigeration unit R.U. is a commercial unit which is mounted at the base 38 of the machine at the rear, as shown in FIGS. 3a and 3b. The cooling coil 36 is connected to the refrigerating unit by tubes 37. The refrigerating unit does not operate constantly but is called into operation according to the temperature of the etching bath. To this end the temperature gauge 27 has a temperature responsive switch which is closed when the temperature exceeds the desired range to connect the line side to the motor of the refrigeration unit. This is an obvious and well known type of control and deemed not necessary to disclose it herein to understand the present invention.

35 In the etching process the acidulous bath generates heat and resultant fumes which it is necessary to reduce and for temperature control the above described refrigeration unit is preferably employed.

Circulating Motor and Pump

40 Before the machine is set into operation the tank is filled with the etching fluid of a composition to be described to the desired level. The fluid which has been previously mixed according to the desired composition and brought to the desired range of temperature may be poured from a pail into the tank or pumped therein.

The combined circulating motor and pump may then be set into operation. Said combination motor and pump is mounted upon the bottom base plate 38 beneath the tank 30 and consists of a motor 40 (FIGS. 1, 2, 3b) and a directly connected driven fluid pump 41. The motor is set into operation by the depression of the button 20 (FIG. 1) on the panel 18 marked "Circumpump." From the suction side 43 of the hydraulic fluid pump 41 there is a duct or tube 44 having an opening to the bottom of the tank (see FIG. 4). The fluid flows by the gravity from the bottom of the tank to the suction side of the pump, and said pump forces it back under pressure through a tube 46 which passes through the back wall of the tank. The tube 46 is connected to a tube 47 which is within the tank and bent downwardly to terminate in the bath so as to discharge the fluid with a forceful swirling motion. This is a relatively important operation in the process since the protective film of the present etching fluid may separate out into its respective components unless the fluid is kept in constant agitation and motion.

45 The circulating motor and pump work independently of all the other units and may or may not be called into operation, depending upon the behavior of the fluid during the etching operation.

Etching Bath

The present machine works upon a principle which is a modification of the well known "Dow" rapid etch method for flat plates covered by Patents Nos. 2,640,763, 2,640,764, 2,640,765, 2,640,766 and 2,640,767. Each of these five patents recognizes the need for and discloses various formulas each of which includes an ingredient for exerting a controlling effect on the action of the nitric acid in a lateral direction to prevent undercutting in a lateral direction.

A solution recommended for an etching bath for etching flat magnesium plates is as follows:

Nitric acid.....	10.5%.
Diethylbenzene.....	7.0%.
"Aerosol" (trademark).....	.40%.
Gelatin.....	From 50 to 125 of 1% stock solution.

All in a water solution.

The above solution in combination with a special machine provides for rapidly etching flat magnesium plates to a depth of ".015"-".018" without any substantial undercutting. However, this solution is not effective for rapidly etching magnesium printing cylinders to a comparable or greater depth without any undercutting. This is especially true for cylinders of small diameter and consequently high curvature of the printing surface. In the present machine a modification of the solution together with a novel means for impinging the solution against the printing cylinder and effecting concurrently its rotation and axial reciprocation will effect etching of a cylinder 2 $\frac{1}{4}$ " diameter or larger to a depth of ".018"-".021" in one step without undercutting.

One improvement consists in modification of the above solution by the complete exclusion of one ingredient, gelatin. This is an important improvement as the gelatin balance in the flat plate bath is very critical. The gelatin deteriorates and the rate of deterioration is governed by a time factor. By exclusion of gelatin a better control of the etch can be obtained. The rate of etch in the present machine is governed only by the number of cylinders processed in a bath. The time elapsed between etches has no effect on the result.

Aside from the modification of the solution, several mechanical improvements are incorporated in the present machine. The "Aerosol" ingredient combined with diethylbenzene forms a protective film which protects the side walls from etching. In the present machine the solution is directed as a continuous forceful spray normal to and against the rotating cylinder and is effected by a motor, a hydraulic pump, and a spray nozzle system. The directing of the acid solution against the cylinder with force and perpendicularly with respect to the axis of rotation causes the acid to penetrate the film and effect the etching operation according to the acid resist on the surface.

The protective film gives the sidewalls of the etched type along radial lines the desired protection against undercutting. Means is also provided to effect the rotation of the cylinder which carries the film around the periphery of the cylinder and build it up along axial lines. The movement of the film in this direction prevents the undercutting in a lateral, or axial direction.

In addition to said film protection, the amount of etchant impinging the cylinder is regulated by a pressure controlling valve so that after said etchant has once been in contact with the cylinder, and lost some of its initial velocity, it is no longer capable of etching.

Spray Motor and Pump

When the tank cover has been closed and the electrical timer has been set for the selected period of operation the depression of the switch button 18 on the panel marked "Spray" (see FIG. 1) will cause the spray motor 50 to be set into operation. The spray motor 50 (FIG. 2) is

mounted on the base 38 and drives a hydraulic fluid pump 51 (FIGS. 2 and 3b), the suction side of the pump receiving fluid fed by gravity from the bottom of the tank 30 by a tube 52, one end of which opens into the bottom wall of the tank (see FIG. 4) and the other is connected by a compression fitting 53 to the suction side to the pump. The pump discharges the fluid at its maximum pressure capacity through a strainer 54 (FIGS. 2 and 3b) and a tube 55 which is connected at one end to the inlet of a three-outlet junction fitting 56. The fluid discharges at one outlet 57 of said fitting 56 to a tube 58 terminating at a fitting 59 which leads the fluid discharge through a tube 60 to a T 61 (FIGS. 2 and 5) leading to the spray nozzle system to be described later. The etching fluid also discharges at a second outlet 62 (FIGS. 2 and 3b) through a tube 63 connected to the pressure gauge 25 mounted on the panel. This will indicate at all times the pressure of the etching fluid. The third outlet 65 (FIGS. 2 and 3b) of the junction fitting 56 is connected by a short tube 66 to a gate valve 67 which is open more or less to enable the etching solution to be by-passed by a tube 68 to a bushing fitting 69 in the back wall of the tank leading to a tube 70 (FIGS. 5 and 6) within the tank. Said tube 70 is bent downwardly as shown in FIG. 6 to terminate and open in the bath to stir the discharge in the solution to aid in the agitation of the etchant.

The adjustment of the shaft of the gate valve 67 to permit the fluid to be directly discharged into the bath and by-pass the nozzles is conveniently effected by a rotatable knob 72 (FIG. 1) mounted on the control panel 18. By bypassing the discharge fluid around the nozzles, it is possible to adjust the pressure of the etching fluid supplied to the nozzles and meter it within very close limits. Thus, the force of the sprayed etchant to produce the desired depth of etch without radial and lateral undercutting can be controlled.

Spray Nozzles

The spray nozzle arrangement now to be described receives the etching fluid from the spray pump at a definite pressure and impinges two opposing sprays perpendicularly against the opposite peripheral surfaces of the rotating printing cylinder. The force of the spray causes the etching acid to pass through the protective film and etch the metal, the radial direction of the spray preventing undercutting in a radial direction, and producing straight or steeply sloping radial walls for the etched type.

Attached to the top of the front and rear walls of the tank are respective fluid manifolds 73 and 74 (FIGS. 5 and 6). More specifically each manifold consists of two parts 75 and 76 fastened together by screws 77. Each part is machined so as to form in combination an etchant fluid reservoir 78, it being understood that the reservoir is closed at its ends. Each manifold is secured to the related tank wall by screws 79 so that the manifolds are midway of the tank. As best shown in FIG. 6, the manifolds are high up in the tank and just beneath the cover 17.

From the sides of the T 61 there are outlet tubes 80 and 81 which through a related elbow 82 have an entrance into the reservoir 78 of the respective manifold 73, 74. When each manifold is completely filled it is built up to the pressure indicated on the pressure gauge 65 and this causes the fluid to be discharged through the nozzles mounted on the top of each manifold as will now be described.

Each manifold has a row of four nozzles 85 screwed into the manifold so as to open into the reservoir 78 and the nozzles have their diffusion slots 86 aimed to direct sprays of the etchant in overlapping fashion to the center of the shaft of the printing cylinder 101, along the spray lines 88 (see FIG. 6). The opposing overlapping fan-like sprays from each of the two rows of nozzles are directed to opposite peripheral surfaces of the rotating

printing cylinder to make certain that if one nozzle does not impinge the spray against a certain area of the printing cylinder, another nozzle or nozzles will take care of this inadequacy.

Printing Cylinder Rotating Means

When the button 26 (FIG. 1) on the operating panel 18 marked "Drive" is depressed the power circuit to the drive motor 100 (FIGS. 1 and 2) is completed and a drive mechanism operated by the motor is set into operation to impart both a rotary motion and axial motion to the printing cylinder 101 (FIG. 4). The electrical circuits for initiating the operation of the drive motor 100 and the other motors are not shown since they are well known.

The drive motor 100 (FIG. 1) is mounted upon the bottom base plate 38 of the machine and through a speed reduction mechanism 102 rotates a pulley 103. The pulley 103 (FIG. 2) rotates a pulley 104 through a belt 105. The pulley 104 is secured to one end of a shaft 106 (FIG. 7) journaled in a casting 108, and the free end of the shaft 106 has secured to it a wide gear 109. The casting 108 is the main support for the drive for the printing cylinder which is located outside of the tank 30. Said casting has three integral feet 110, 111, 112 (FIG. 7) which are fastened by respective screws 113 to the left side wall (as viewed in FIG. 1) of the etchant tank.

Journalized in the bracket 108 outside of the tank is a rotatable and axially shiftable shaft 115 to which is fixed a gear 116 which meshes with the gear 109. Gear 109 is wider than the inter-meshing gear 116, in order to continuously retain the engagement of gears 109 and 116 in the different relative positions of the gear 116 and shaft 115. The left end of the shaft 115 passes through the tank 30 and is supported by the left side wall of the tank by a support described as follows: A cylindrical hollow bearing 119 passes through a hole 120 in the tank wall and within the tank it has an annular flange 121 bearing against the inside wall of the tank and an intermediate ring gasket 122. Outside of the tank wall there is provided a tightening nut 123 engaging the threaded portion 124 of the cylindrical bearing. Tightening of the nut 123 places compression on the gasket 122 and securely attaches the cylindrical bearing 119 to the tank wall in a leak-proof manner. The shaft 115 passes through the center of the cylindrical bearing 119 and to furnish the shaft 115 with a leak-proof seal, there is fitted over the shaft 115 a series of five lubricated rings 125 which alternate with separating washers 126 and an end ring 127. A compression nut 128 threaded on the threaded portion 129 of the cylindrical bearing 119 compresses the assembly together and against an annular ring 130 of the cylindrical bearing 119 outside of the tank. The above construction provides a sealed lubricating bearing for the shaft 115 where it passes through the left side wall of the tank 30.

The left end of the shaft 115, which is in the etching tank 30, has attached thereto a gear 135 (see FIG. 4) on each side of which there is attached a thrust side plate 136 of greater diameter than the outside periphery of the gear.

To the right tank wall which is opposite to the left tank wall that the above described drive mechanism passes through, there is attached an upstanding bracket 140 having a semi-circular shaft bearing notch 141. Similarly, the left side of the tank where the aforesaid drive mechanism projects through there is secured a bracket 142 having a semi-circular shaft bearing notch 143, both notches being lined with a low friction, acid resistant bearing material.

The printing cylinder arbor support comprises several parts which, when assembled together, support the printing cylinder 101, and in such manner that the assembly

may be made before insertion in the tank of the machine for processing, then easily inserted in the machine on the liner 144 of the notches 141 and 143 of respective brackets 140, 142 and after processing the cylinder and arbor 5 support may be withdrawn from the machine for washing, etc. It comprises a lefthand annular plate 146 (FIG. 7) attached to the lefthand arbor shaft 147 by a set screw 148. Similarly, a right hand annular plate 150 is secured to the righthand arbor shaft 151 by a set screw (not 10 shown). Plates 146 and 150 each have shoulders or annular flanges 152 over which the printing cylinder 101 is placed. The external periphery of the shoulders of the annular plates 146 and 150 conforms to the inside diameter of the printing cylinder 101 and being the same 15 size said printing cylinder 101 firmly fits on both supporting plates 146 and 150. As the printing cylinder 101 is so assembled a threaded end 153 of the lefthand arbor shaft 147 is manually screwed into the internal threaded hole 154 of the annular plate 150 to fit the printing cylinder 101 tightly between plates 150, 151. A ring gasket 155 of a compression type assists in making a tight unitary assembly. To facilitate handling of the assembled printing cylinder arbor support and assist in the screwing of the arbor shaft 147 into the annular plate 150, each 20 shaft 147 and 151 carries respective knurled cylinders 156, 157. After the assembly has been made as shown in FIG. 7, the assembled printing cylinder arbor support carrying the printing cylinder 101 to be etched is placed in the etching tank with the shafts 147 and 151 fitting in the semi-circular bearing notches 141, 143 of the respective brackets 140, 142. When so placed and journalized a gear 158 (see FIG. 4) secured to the end of the shaft 151 meshes with the gear 135 and is caused to fit in between the thrust side plates 136 of gear 135. When this gear 25 drive relationship is made, starting of the drive motor 100 will rotate the printing cylinder 101 after which the spray motor 40 will be started to cause the spray pump 41 to spray the etching solution upon the peripheral surface of the now rotating printing cylinder 101. During 30 this rotation it is desirable to axially reciprocate the printing cylinder 101 to cause the uniform application of the etchant and to spread the film along an axial direction and more evenly over the periphery.

Means to Effect Axial Reciprocation of Printing Cylinder

As best shown in FIGS. 4 and 7 there is secured to the casting or bracket 108 by screws 159 a bracket 160. A circular disk 162 fits in a hole in the underside of the bracket 160 and said disk has an integral cam follower projection 161 (see also FIG. 8). Fixed to the end of shaft 115 is a cam cylinder 163 formed with a continuous cam slot 164 around its periphery in which fits said cam follower projection 161. While not shown the underside of the cam follower projection 161 is circular to conform to the circumference of the cylindrical cam at the bottom of the cam slot 164. The cam slot 164 is continuous and has one complete righthand thread and one complete left-hand thread having a common point of intersection and joining of the ends of the cam race. The effect of this cam slot 164 and its engagement by the stationary cam follower 161 is to move shaft 115 and the printing cylinder 101 axially in one direction and then the other as said shaft 115 is rotated. During this operation the reciprocable axial movement of thrust gear 135 carried by shaft 60 115 shifts the gear 158, shaft 151 and printing cylinder 101 similarly and the narrow gear 116 slides back and forth over the gear 109 without, however, effecting a demeshing of the teeth of the gears.

Mode of Etching Operation

The present invention embodies an improved mordant spraying system. In applicants' copending application Serial No. 671,233, filed July 11, 1957, the mordant is sprayed upwardly from rows of nozzles aimed at the center of the printing cylinder which is not submerged 70 in the etching solution in the tank.

In the present machine and the one shown in the above identified application, upon impingement of the spray on the surface of the cylinder, the acid etches the cylinder and the Aerosol-diethylbenzene combination forms an acid resisting film which protects the sidewalls from etching. In the machine of the above identified application the horizontal rotation of the cylinder carried this film around the cylinder which caused this film to build up more on the axial lines of the cylinder than on the radial lines. This gave the sidewalls of the axial lines somewhat more protection so they did not etch the cylinder laterally as much as along radial lines which received less sidewall protection due to the natural force of gravity allowing the Aerosol-diethylbenzene film to drain off more readily. This necessitated a closer control of the etching to maintain a balance between the undercutting of the radial lines and the shouldering off of the axial lines.

The present improvement has been designed and proven to give more latitude and better control in the etching. To this end there is provided a tray 165 (FIGS. 5 and 6) which extends almost the width of the tank and is supported by the brackets 140 and 141. When the printing cylinder is in the brackets 140, 141 the level of the mordant in the tray is above the horizontal center line of the printing cylinder. Each of the rows of spray atomizing nozzles 85 is aimed at the center of the cylinder so that the spray impinges on the cylinder at the level of the mordant and fills the tray 165 to the desired level.

Since more than half of the cylinder is submerged, the quantity of mordant is equally applied to all surfaces of the cylinder. There is no gravity drain-off directly from the cylinder when submerged so that when a surface portion of the cylinder emerges from the mordant, the Aerosol-diethylbenzene film has been equally applied over the entire surface of the cylinder. The impingement of the etching acid from the nozzles 85 causes etching of the surface which is equal for both axial and radial lines. Rotating the printing cylinder in the mordant does not cause any appreciable etching as the cylinder receives a protective film from the Aerosol-diethylbenzene combination and it takes the force of the spray to break through this film to cause etching.

A further advantage is obtained by this etching applying arrangement in the reduction of the amount of mordant hitting the sidewalls of characters being etched. When the etching mordant is brought up from the bottom such as from "D" (see FIG. 6), the mordant is free to go at right angles in both directions after hitting the cylinder. This right angle deflection would be sufficient to cause some lateral etching of the sidewalls. At point "E" the two right angle deflections would meet and be deflected upwards causing additional etching. When the nozzles are moved so as to impinge at the mordant level,

the acid is deflected upwards towards "F." The mass of the mordant at the cylinder level absorbs the mordant that is deflected downwards, therefore, half of the lateral etching caused by the acid coming off at an angle is eliminated. This makes it possible to obtain better sidewall protection and etch to greater depths with less undercutting.

While there have been shown and described and pointed out the fundamental novel features of the invention, it will be understood that various omissions and substitutions and changes in the form and details of the device illustrated and in its operation may be made by those skilled in the art, without departing from the spirit of the invention. It is the invention, therefore, to be limited only as indicated by the scope of the following claim.

What is claimed is:

In a machine for spraying and coating a metal printing cylinder surface with a nitrous acid etchant solution containing in admixture therewith ingredients comprising a removable acid resistant film for preventing undercutting of type walls, a tray filled with said etchant solution to a predetermined liquid level, means for axially mounting and submerging the printing cylinder for rotation in said tray with said liquid level slightly above the horizontal axis of the cylinder, a first row of spray nozzles disposed on one side of said cylinder, a second row of spray nozzles disposed on the opposite side of said cylinder, said spray nozzles being provided with diffusion slots to forcibly dispense a thin sheet of overlapping sprays of said etchant solution, means for axially rotating said cylinder past said first and second rows of nozzles, respectively, while submerged to coat the surface of said cylinder uniformly over the entire peripheral surface with said acid resistant film, mounting means for arranging said first row of nozzles at an angle so that the thin spray sheet of etchant therefrom strikes the peripheral surface of said cylinder perpendicularly and slightly below the level of the solution in said tray, and mounting means for arranging said second row of nozzles at an angle so that the thin spray sheet of etchant therefrom strikes the opposite peripheral surface of said cylinder perpendicularly and slightly below the level of the solution in said tray.
